SUCTION CLEANER

Donald G. Smellie, Canton, Ohio, assignor to The
Hoover Company, North Canton, Ohio, a cor-
poration of Ohio

Application December 18, 1936, Serial No. 116,516

9 Claims. (Cl. 15—6)

The present invention relates to suction cleaners in general and particularly to new and novel agitator-driving means in a suction cleaner. More specifically the invention comprises agitator-driving means in a suction cleaner which means convert rotary motion to reciprocating motion by the use of rotating unbalanced masses which form a system in which undesirable forces are eliminated within the system itself.

10 It is an object of the present invention to provide a new and improved suction cleaner. It is a further object of the invention to provide new and improved agitator-actuating means in a suction cleaner. A further object of the invention is to provide a suction cleaner in which rotary motion is converted to reciprocating motion by means of rotating unbalanced masses. A still further object is the provision of a suction cleaner in which a plurality of rotating unbalanced 15 masses are so related that the undesirable forces are cancelled within the system while the desirable forces accomplish the intended functional result. Still another object of the invention is the provision of a suction cleaner in which the 20 rotating force of the driving motor of the suction cleaner is converted into a reciprocating motion of the cleaner agitator through the cooperation of rotating unbalanced masses which form a system within which the functionally undesirable forces are cancelled. These and more 25 specific objects will appear upon reading the following specification and claims and upon considering in connection therewith the attached drawings to which they relate.

30 Referring now to the drawings in which a preferred embodiment of the present invention is disclosed:

Figure 1 is a side elevation of the suction cleaner embodying the present invention with 35 certain parts broken away and shown in section;

Figure 2 is a bottom view of the cleaner shown in Figure 1 with certain parts broken away and shown in section;

Figure 3 is a section upon the line 3—3 of 40 Figure 2 showing the system of rotating unbalanced masses;

Figure 4 is a rear view of the cleaner shown in Figures 1 and 2;

Figure 5 is an enlarged section through the 45 cleaner nozzle, similar to the showing thereof in Figure 1, and shows the connection of the agitator-actuating means to the agitator;

Figure 6 is a partial section similar to Figure 5 showing a modified agitator construction.

50 In the drawings a modern suction cleaner is

disclosed comprising a nozzle 1 which is connected to a fan chamber 2 provided with an exhaust outlet 3. A motor casing 4 is positioned in the rear of the fan chamber 2 and houses a driving motor 5. A suction-creating fan 6 positioned within the fan chamber 2 is driven by the motor 5 to create a reduced pressure within nozzle 1 and to draw air therefrom and exhaust it through the exhaust outlet 3 into a removably secured dust bag 7. The reduced pressure within the nozzle 1 effects the lifting of the surface covering undergoing cleaning into contact with the front and rear nozzle lips 8 and 9 respectively. The nozzle lips are movably positioned with respect to the surface covering undergoing cleaning, as is the remainder of the cleaner casing, by front and rear supporting wheels 10 and 11. As in the usual cleaner construction nozzle-height-adjusting means, indicated generally by the reference character 12, are connected to the front wheels to make possible the raising and lowering of the nozzle lips relative to a surface covering undergoing cleaning. Also, as in the usual cleaner construction, a pivoted handle 13 is provided and is formed with bifurcated arms 14, 14 which are pivoted upon the opposite sides of the motor casing 4. Suitable handle-positioning means, indicated generally by the reference character 15, are provided which, in a well known manner, position the handle in a fixed position or within a range of movement.

Within the cleaner nozzle 1, and positioned between the lips 8 and 9, is an agitator 16 which comprises, in the modification shown in Figures 1 to 5, inclusive, spaced surface-contacting-and-beating elements 17, 17, and which, in the modification shown in Figure 6 comprises in addition to the elements 17, 17 a centrally positioned brush element 18 which is removably secured as by a screw 19. In each of the modifications 20 agitator 16 is pivotally mounted at its ends in bearings 20, 20 and is adapted to be reciprocated or oscillated, as illustrated by the full and dotted line positions in Figure 5. This movement results in alternate contact with the surface covering undergoing cleaning of first one beater element 17 and then the other, each element delivering thereto a positive beating blow. With the agitator of Figure 6 provided this beating action of the elements 17, 17 is supplemented by 25 the arcuate rotary brushing motion of the brush 18.

The alternate rotary motion of the agitator, or its reciprocation, is accomplished by means of a new and novel mechanism which converts the 30

rotary motion of the driving motor 5 into the alternate rotary motion of the agitator. This power-transmitting and converting mechanism will now be described.

- 5 The motor 5 within the casing 4 extends, in its rotary shaft portion 21 through the rear face of the casing 4 into a housing 22 where it carries a driving pulley 23. A power-transmitting belt 24 connects the driving pulley 23 to a second pulley 25 which is also positioned within the housing and which is carried upon the end of a rotatable shaft 26. Shaft 26 is itself rotatably mounted within a bearing seat 27 positioned at the end of a spindle 28 rotatably mounted within bearings 29, 29 on the under side of motor casing 4. The rotatable shaft 26 is itself rotatably mounted in spaced bearings 30, 30 positioned within the bearing seat 27.
- Shaft 26 extends forwardly from its supporting bearings 30, 30 in a direction which is substantially parallel to the shaft 21 of the motor and to a point immediately in the rear of the rear wall of nozzle 1. Forward of bearing seat 27 shaft 26 is enclosed within a concentric tube 31 which is itself seated at its rear end within the bearing seat and at its forward end within the casing 32 of the unbalanced mass system.

Within casing 32 an unbalanced mass comprising a gear 33 is positioned, the gear being rotatable with the shaft and both being rotatably carried by bearings 34, 34. Horizontally spaced from unbalanced gear 33 is a second unbalanced gear 35 the teeth of which mesh with the teeth of gear 33 and which is itself rotatably supported by bearings 36, 36. As is clearly illustrated in Figure 3, the unbalance of the two rotating gears is out of phase 180 degrees. The gear 33 being keyed to the shaft 26 and the two gears being in mesh, it follows that the gears 40 rotate together and in opposite directions.

The casing 32 of the unbalanced mass system is connected to the agitator 16 by means of a fixedly seated pin 37. An aperture 38 is formed in the rear wall of casing 1 through which the pin 37 extends and a flexible collar 39 of a suitable material, such as rubber, seals to the opening 38 and to the pin 37 to prevent air leakage. The opening 38 is sufficiently larger than the pin to permit lateral displacement of the latter. The forward end of pin 37 seats within a metallic seat 40 which is carried by the agitator 16 in an enclosing insulated body 41 of resilient material.

In the operation of the suction cleaner constructed in accordance with the present invention, the rotation of the driving motor results in the rotation of the fan 6 and the creation of a reduced pressure within the nozzle 1. The surface covering undergoing cleaning is lifted 60 into contact with the nozzle lips 8 and 9 and into contact with agitating elements 17, 17 of agitator 16. Cleaning air is drawn into the nozzle under the lips and is exhausted from the fan chamber through the exhaust outlet 3 into the filtering bag 7. The rotation of the motor also causes the rotation of the unbalanced masses 33 and 35 which are connected to the motor shaft by the pulleys 23 and 25, the belt 24, and the elongated rotating shaft 26. Upon being rotated 70 the eccentric masses of the rotating gears 33 and 35 exert centrifugal forces about their axes of rotation. As the two gears are identical in all respects, are rotated in opposite directions, and as their unbalance is spaced exactly 180 degrees, as illustrated in Figure 3, a result is

produced in which vertical components of the centrifugal forces of the masses are additive and also in which the horizontal components of that force mutually cancel. This is clear from an inspection of Figure 3 in which it is obvious that as the unbalanced masses move downwardly they tend to draw the entire supporting mechanism in that direction, and the same is true when they move upwardly. Also, as the unbalanced masses move toward each other and from each other at the same time and in the same relative positions relative to their axes, it follows that the horizontal components of force which are set up are mutually opposed and so cancel. As a result, then, of the rotation in the system of unbalanced masses the entire casing 32 is moved upwardly and downwardly with a periodicity which is dependent upon the speed of rotation of the unbalanced masses. This movement of casing 32 is permitted by the mounting 20 of shaft 26 which is as described, carried by the bearing seat 27 which is itself rotatably mounted through a spindle 28 upon bearings 29, 29 thereby permitting of the pivotal movement of the shaft 26 about the spindle 28 as an axis. The opening into the casing 22 through which the shaft 26 extends is of sufficient size to permit this pivotal movement of the shaft 26.

The reciprocating vertical displacement of casing 32 is transmitted through the opening 38 in the rear wall of the cleaner nozzle by the pin 37 to the agitator 16. The pin 37 moves in a vertical plane with the casing 32 and as it moves it pivots the seat 40 about the agitator axis through the bearings 20, 20. The result is the alternate arcuate rotary motion of the agitator 16 and the beating of the surface covering undergoing cleaning by the elements 17, 17 coupled with the brushing of that covering by the brush element 18 when that element is present.

If it is desired the pivoted unbalanced system can be provided with stabilizing springs 42, 42 carried by the cleaner casing and which resistingly oppose the pivotal movement of the shaft 26 through contacting its surrounding casing 31. 45 This stabilizing feature is not absolutely essential but may be provided where it is desired to limit within a certain range the pivotal movement of the system.

I claim:

1. In a suction cleaner, a body, a rotary driving motor, a reciprocating surface covering agitator carried by said body for movement in a constrained path, and means to drive said agitator from said motor comprising a system of 55 rotating unbalanced masses driven by said motor and which exert additive forces in a direction to move said agitator in said path and mutually cancelling forces at right angles to the first-mentioned direction, means mounting said system for movement in the direction of said additive forces and connecting said system to said agitator, whereby said additive forces are imparted thereto.

2. In a suction cleaner, a body including a 65 nozzle, suction means connected to said nozzle, a rotary driving motor, a reciprocating surface covering agitator movable relative to said nozzle and means to drive said agitator from said motor comprising a plurality of rotatable unbalanced masses driven by said motor, means mounting said masses on said body for reversible translation as a unit in a given path, the unbalance of said masses being such that the component 70 of forces set up by said masses in rotation which 75

tends to move said masses in said path are additive while those transverse thereto cancel, and means to transmit the movement of said masses as a unit to said agitator, whereby the straight-line impulse only is imparted to the latter.

5. 3. In a suction cleaner, a body, a rotary driving motor, a surface covering agitator mounted for constrained reciprocation and means to drive said agitator from said motor comprising a system of rotary unbalanced masses driven by said motor and movable as a unit, said unbalanced masses being adapted to set up centrifugal forces when rotating which forces are additive in their components parallel to a predetermined plane 10 and are cancellative in their components perpendicular to that plane, means mounting said system for translation relative to said body under the action of said additive forces, and means to transmit the movement of said system to said 15 agitator to actuate the latter within its constrained path.

4. In a suction cleaner, a body, a rotary driving motor, a reciprocating surface covering agitator and means to drive said agitator from said motor, 20 said means comprising a driven rotating shaft pivoted to said body, a system of oppositely rotating unbalanced masses driven by and connected to said shaft at a distance from the pivotal axis of said shaft to set up additive forces about 25 said axis and cancellative forces in the direction thereof, said system being movable with said shaft, said shaft being adapted to reciprocate under the centrifugal forces set up by said masses, and means to transmit the reciprocation motion at 30 the end of said shaft to said agitator to reciprocate the latter.

5. In a suction cleaner, a body having a nozzle, suction-creating means connected to said nozzle, a rotary driving motor, a reciprocating surface 40 covering agitator in said nozzle and means to drive said agitator from said motor, said means comprising a rotatable shaft spaced from and extended substantially parallel to the axis of said motor, a power-transmitting belt extended between a rotating part of said motor and said 45 shaft, means mounting said shaft on said body for pivotal movement about an axis perpendicular thereto and closely adjacent its point of connection to said belt, a system comprising a plurality of unbalanced masses mounted for 50 pivotal movement with said shaft and driven by said shaft, said shaft being adapted to pivot

reversibly under the centrifugal forces set up by said masses, and means to transmit the reciprocating movement of said shaft to said agitator.

6. In a suction cleaner, a body, an agitator mounted on said body for constrained pivotal movement about an axis on said body, and means to reciprocate said agitator comprising a system of driven rotatable unbalanced masses connected to said agitator and mounted for linear reciprocation transversely of the axis of said agitator, the 10 unbalance of said masses being such that the components of force set up by said masses are additive transversely of said axis and cancellative in their components parallel thereto.

7. In a suction cleaner, a body, an agitator mounted on said body for constrained movement in a predetermined path, and means to reciprocate said agitator in said path comprising a system of driven rotatable unbalanced masses movably mounted on said body and connected to said 20 agitator, the unbalance of said masses being such that the forces set up by rotation are cumulative in a direction to effect reciprocation of said agitator and are cancellative in other directions, whereby the vibration transmitted to the supporting body is a minimum.

8. In a suction cleaner, a body having a nozzle, suction-creating means connected to said nozzle, an elongated agitating element mounted in said nozzle for reciprocation relative to said nozzle, and means to actuate said element comprising a system of driven rotating unbalanced masses movably carried by said body and connected to said element, the unbalance of said masses being such that the generated forces are cumulative in 30 one direction and cancellative transversely of that direction, said means being connected to said element to actuate it transversely of its length.

9. In a suction cleaner, a body including a nozzle, suction-creating means connected to said nozzle, an agitator movably mounted on said nozzle, and means to reciprocate said agitator relative to said nozzle comprising a system of rotating unbalanced masses carried by said body, the unbalance of said masses being such that the 40 generated forces are cumulative in one direction and cancellative in other directions, whereby no turning torque is transmitted to the supporting body and to the agitator, and means connecting said system to said agitator to transmit the 45 cumulative forces thereto.

DONALD G. SMELLIE.
